UNITED STATES PATENT OFFICE.

MORGAN J. GRIFFITH, OF CHICAGO, ILLINOIS.

SWITCH-HEATING APPARATUS.

Application filed May 10, 1926. Serial No. 107,913.

This invention relates to a heating apparatus designed for melting the snow and ice that usually gathers in a railroad switch.

There are numerous instances where the snow and ice between a track and switch point have prevented the proper operation of the switch point which has frequently resulted in accidents and loss of life.

It is an object of this invention to prevent such occurrences in the provision of electrical heating means designed to melt the snow and ice in a railroad switch.

The invention comprises the novel structure and combination of parts hereinafter described and more particularly pointed out and defined in the appended claims.

In the accompanying drawings which illustrate certain preferred embodiments of this invention and in which similar reference numerals refer to similar features in the different views,

Fig. 1 is a plan view of a railroad switch showing portions of the rails in dotted lines to better illustrate the invention;

Fig. 2 is an enlarged sectional view upon the line II—II of Fig. 1;

Fig. 3 is a side elevational view of a railroad switch illustrating a slightly modified form of the invention;

Fig. 4 is a top plan view of the switch shown in Fig. 3 with the rails shown in dotted lines;

Fig. 5 is an enlarged sectional view upon the line V—V of Fig. 4;

Fig. 6 is a fragmentary elevational view of one of the heating conductors with a part of the insulation removed;

Fig. 7 is an enlarged sectional view upon the line VII—VII of Fig. 6;

Fig. 8 is a top plan view of a railroad switch with the rails shown in dotted lines, illustrating a further modification of the invention with parts omitted;

Fig. 9 is an enlarged sectional view upon the line IX—IX of Fig. 8;

Fig. 10 is a top plan view of a railroad switch illustrating a further modification of the invention; and

Fig. 11 is an enlarged sectional view upon the line XI—XI of Fig. 10.

In referring to Figs. 1 and 2, it will be observed that I have shown a portion of a railroad track comprising the tracks 1 and movable switch points 2 resting upon plates 3 supported upon the cross ties 3. Beneath each cross plate there is a recess 5 in the

tie, which recess is located between the track 1 and switch point 2. A flexible metal cable 6 is positioned in the recesses between each rail and its switch point and is connected in series with its adjacent rail. To this end, one end of each cable 6 is connected to its rail 1 as indicated at 7. The other end of each cable projects to one side of the track as indicated at 8 and 9. Each of the ends 8 and 9 connects with a coil 10 of a low voltage transformer 11. To complete the circuit in each cable each coil 10 is connected by a conductor to the proper rail. Thus the coil 10 on the terminal 8 is connected by a wire 12 to the near rail 1, while the coil 10 on the terminal 9 on the farside cable is connected by a conductor 13 with the farside rail.

It will be noted that the cables 6 lie between the rails 1 and the switch points 2 and consequently are capable of heating and melting any ice or snow that may be lodged therebetween.

In Figs. 3 to 7, there is shown an insulated heating conductor 14 positioned against the web of the rail 1 and confined by wooden members 15 clamped against the side of the rail. Each wooden member has a recess or groove 16 for receiving the conductor. Each conductor 14 is positioned within the limits of the movable switch points 2 and one end of each is connected to the adjacent rail 1 indicated at 19. The other end of each conductor 14 is connected with a coil 10 of a low voltage transformer 11. The near rail 1 is connected to the proper coil 10 by a wire 17, while the far rail 1 is connected to the proper coil by a wire 18. Consequently the current passing through each cable will return through the adjacent rail which is hence in series with the conductor.

In Figs. 8 and 9, there is shown an insulated cable or heater tube 20 which is confined against the web of each rail by a wooden member 21 clamped to the rail. Each wooden member has a groove 22 lined by a sheet of copper 23 for receiving the cable 20. One end of each cable 20 is connected to ground through its adjacent rail 1 as indicated at 24. The other end of each cable 20 beyond the movable switch points 2 leads to a source of power. For this purpose, the terminals 20^a and 20^b are shown.

In Figures 10 and 11 there is shown a heater tube or cable 20 confined between each

2

rail 1 and its switch point 2 in suitable recesses 5 in the ties, as in the first form. These cables 20 are connected at one end to transverse conductors 20^a and 20^b, respectively which may be part of the same. Feed wires 26 connect with the heater tubes or cables 20 for supplying the current. The opposite ends of the conductors 20 in Figure 10 may be connected to ground or to 10 turn to the power line by the terminals 20^a and 20^b. As shown in Figure 11 copper plates 20^c may be mounted in the recesses 5 to aid in directing the heat to melt away snow and ice on the plates 4 and between the 15 rails and switch points.

It will be appreciated that when snow or ice collects between the rails and switch points, it is only necessary to turn on the current for heating the heating tube or 20 cables for melting the ice or snow, so that the switch points can always be fully operated.

It will be apparent that the manner of 25 mounting the heater tubes or cables of this invention assures the application of heat in an efficient manner and without undue waste at the desired points.

I am aware that many changes may be 30 made and numerous details of construction may be varied through a wide range without departing from the principles of this invention and I therefore do not purpose limiting the patent granted hereon otherwise than necessitated by the prior art.

35 I claim as my invention:

1. The combination with a railroad switch and ties supporting the same, of metallic plates engaged between the rails and said ties, recesses laterally traversing said ties 40 underneath said plates, and electric heating means substantially parallel to said rails and

disposed in said recesses in close proximity to said plates.

2. The combination with a railroad switch and ties supporting the same, of metallic 45 plates engaged between the rails and said ties, recesses laterally traversing said ties underneath said plates, a flexible metallic casing substantially parallel to said rails and disposed in said recesses in close proximity to said plates, and electric heating means in said casing.

3. In combination, a railroad switch including a plurality of rails, ties for supporting said switch, each of said ties having a 55 transverse groove disposed in alignment with the grooves of the adjacent ties, metallic tie plates on top of said ties under said rails, said grooves being directly below said tie plates and in proximity to said rails, 60 and electric means for heating said switch comprising conductors extending from tie to tie and disposed in said grooves, said conductors serving to heat said switch through said plates.

4. In combination, a railroad switch including a plurality of rails, electric means 70 for heating said switch comprising a pair of conductors disposed in proximity to said rails, and a low voltage transformer including primary and secondary windings for supplying energy to said conductors, each of said conductors being grounded through the associated rail at one end and having its other end connected to a secondary winding 75 of said transformer, said secondary windings being grounded through said rails to complete the heating circuits.

In testimony whereof I have hereunto subscribed my name.

MORGAN J. GRIFFITH.
